UNITED STATES PATENT OFFICE.

ARICOLA L. CARPENTER, OF MOUNT VERNON, NEW YORK.

RAILWAY-SIGNAL.

No. 839,549.

Specification of Letters Patent.

Patented Dec. 25, 1906.

Application filed September 19, 1905. Serial No. 279,118.

To all whom it may concern:

Be it known that I, ARICOLA L. CARPENTER, a citizen of the United States, residing at Mount Vernon, in the county of Westchester, State of New York, have invented certain new and useful Improvements in Railway-Signals; and I do hereby declare the following to be a full, clear, and exact description of the invention, such as will enable others skilled in the art to which it appertains to make and use the same.

This invention relates to electropneumatic railroad signaling apparatus.

One object of the invention is to provide means for indicating the distance of a railroad-train from any station or point along the line of road.

Another object of the invention resides in the provision of mechanism along the line of the road wherein an element of the mechanism is actuated by the wheels of the train and through the instrumentality of connections between said mechanism and an annunciator or the like at a distant point determine the distance of a railroad-train from the station or point along the line of road at which the annunciator or other mechanism is arranged.

A still further object of the invention resides in the provision of an electropneumatic mechanism associated with the road-bed and a station or other point, whereby the location of a train may be determined automatically from a distant point.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the present invention.

In the accompanying drawings, Figure 1 is a top plan view of my invention illustrating a track and tie with which my improved mechanism is associated. Fig. 2 is a sectional view on the line *a a* of Fig. 1. Fig. 3 is an enlarged vertical sectional view of the track-valve casing, including the cap and valve-heads, together with the valve-stem, adjusting-nut, and helical-spring connection. Fig. 4 is an enlarged detail perspective view of the air-cylinder. Fig. 5 is a vertical sec-

tional view on the line *b b* of Fig. 1. Fig. 6 is a plan view of a modified form of lever. Fig. 7 is an elevational view of Fig. 6.

Referring now more particularly to the accompanying drawings, the reference characters 1 and 2 designate a rail and tie, respectively, these elements being of the usual or of any appropriate construction and arrangement.

A valve-casing 3, having rear side flanges 4, is secured to the web 5 or other part of the rail through the instrumentality of bolts or the like 6. The forward part of the valve is curved into neck form, as at 7, and provided with a screw-threaded perforation 8, leading 70 into the chamber of the valve, there being a hose-pipe connection 9, having a nipple 10 fitted in one end, which latter is fitted in the screw-threaded opening 8 of the neck 7 of the valve 3, the opposite end of the hose-pipe 9 having a nipple 11 secured thereto, upon which fits a union-nut 12, adapted to embrace a nipple 13, secured in the bottom of the air-cylinder 14, which latter is disposed upon the tie 2 preferably directly opposite 80 the valve 3 and is provided with a base-flange 14^a, having perforations 15 therein, through which are passed suitable fastenings 16 for securing the air-cylinder tightly upon the tie. 75

The valve-casing 3 has its upper end 85 turned upwardly, as at 16^a, and provided with a central perforation 17, through which latter is passed a screw-threaded stem 18 of a cap 19, the beveled inner end of the upwardly-turned portion 16^a of the top of the valve resulting in a seat 20 interiorly of the valve-casing for the proper seating of the valve-head 21, secured upon the screw-threads of the stem 18 and held against accidental displacement by means of the nut 22. It will 95 be observed that the under surface of the cap 19 is hollowed, as at 23, whereby the extremities 24 of the cap-head may embrace the upwardly-turned portion 16^a of the valve-cylinder whenever the cap 19 is depressed for a purpose presently explained. The lower end of the valve-head 21 is reduced to form the shoulders 25, with which latter engages a helical spring 26, whose lower end rests directly upon the bottom of the valve-casing, as 105 clearly shown in the drawings, the tendency of the said helical spring being to force the inclined upper face of the valve-head 21 into engagement with the correspondingly inclined face of the top of the valve cylinder or 110

casing to prevent escape of air from the latter until the cap-head 19 is engaged and forced downwardly against the action of the spring.

The air-cylinder 14 is provided with a perforation 27 in its top through which a piston-rod 29 passes and which latter is provided with a head 30, designed to tightly fit the inner walls of the air-cylinder, there being a helical spring 31 arranged within the air-cylinder between the upper face of the piston-head 30 and the top of the cylinder, the spring encircling the piston-rod 29. An upwardly-directed arm 32 is disposed at one side of the flanged head 33 of the air-cylinder and is provided in its upper end with an eye or perforation 34, in which is pivoted, by means of an insulating-pivot 35, one end of the contact-lever 36, which latter is also provided with a perforation intermediate its ends, whereby it may fit over the upper end of the piston-rod 29, the free end of the contact-lever 36 extending through an opening 37 in the upright 38, arranged opposite the arm 32 and which upright is provided with lateral ears 39 and 40, each having a binding-post and contact-point 41 and 42, respectively, the said contact-points being designed to coöperate with the free end of the contact-lever in its raised or lowered position, whereby the electrical circuit may be made and broken through the respective wires 43 and 44, there being another electrical wire 45 connected, by means of a rivet or the like 46, to the contact-lever 36 near its point of pivot, as clearly shown in the drawings.

Connected in the bottom of the air-cylinder 14 at a point preferably opposite to the connection of the nipple 13 is a valved air-inlet nipple 47, to which is connected a nut-union 48, connecting at its opposite end with another nipple 49, arranged in the end of a hose-pipe connection 50, leading to a suitable air-tank. (Not shown.) The valve 47 of the nipple 47 regulates the air-supply.

In order that the degree of pivotal movement of the contact-lever 36 may be adjusted, the upper screw-threaded end 29' of the piston-rod 29 has upper and lower pairs of adjusting-nuts 51 and 52, respectively, it being obvious that when the pairs of nuts are adjusted toward and away from each other upon the screw-threaded portion 29' of the piston-rod 29 the degree of movement of the contact-lever 36 will be decreased or increased according to the adjustment of said nuts. Of course the opening 37 in the arm 38 is of sufficient diameter to permit of proper movement of the free end of the contact-lever and that the opening intermediate the ends of the latter is somewhat larger than the diameter of the piston-rod 29.

From the foregoing it will be understood that when air enters the bottom of the cylinder through the inlet-port 47, which is of a smaller diameter than the outlet-port 13,

some of the air will pass through the hose-pipe connection 9 and into the valve-cylinder 3, forcing the valve-head 21 into close engagement with the top of its casing to prevent the escape of air through the enlarged opening 17, surrounding the stem 18 of the valve-cap 19, while other air will force the piston-head 30 upwardly into the cylinder 14 against the action of the spring 31, causing the pair of nuts 52 to contact with the under surface of the contact-lever and raise the same into electrical communication with the contact-point 41, which is its normal position and where it is held in electrical communication with a station at a distant point until the wheels of a train (not shown) contact with the cap-head 19, consequently forcing the valve-head 21 downwardly against the action of the spring 26 and exhausting the air from the valve-casing, the hose-pipe 9, and the air-cylinder 14, permitting the contact-lever 36 to break from the contact-point 41 and drop into engagement with the contact-point 42, closing a circuit and warning an operator or other person at some distant point of the location of the particular train contacting with the cap-valve 19, it being seen that the pair of nuts 51 contact with the upper face of the contact-lever 36 upon the dropping of the piston 30 and positively pull the contact-lever downwardly therewith. After the train has passed (the track-valve then being closed) the air-pressure is gradually increased in the cylinder until it again raises the piston and the contact-lever to its normal position, together with the valve-head 21, within the track-valve casing 3. It will thus be seen that the device is automatic in operation. In practice the hose-pipe connections 9 and 50 are armored and different elements insulated from one another where essential, and it will be seen that in order to prevent air accumulating in the air-cylinder 14 above the piston 30 there is provided a small outlet 54 in the top of the casing. It will be seen also that by reason of the peculiar formation of the under face of the cap-head 19 the downward movement of the valve-stem 18 is limited, for it engages with the correspondingly upwardly-formed end of its valve-casing.

In order to make and break a series of circuits, I construct the contact-lever somewhat differently from the form of contact-lever 36, heretofore described. This modified form of lever is shown in Figs. 6 and 7, wherein it will be seen that the lever 36' has wings *a* and *b* formed upon opposite sides thereof intermediate its ends, the end *c* of the lever being adapted for hinged support in the upright 32 at one side of the casing 14 and the opposite end of the same being bent upwardly, as at *d*, for engagement with the upper and lower studs *e* of the bracket *f*. Secured by means of suitable fasteners *g*

respectively to each of the wings *a* and *b* of the contact-lever 36' are pairs of flexible contact-strips *h* and *i*. It will be observed that the strips *h* and *i* are, by reason of the fasteners *g*, which are properly insulated, spaced from the contact-lever 36' and project through the slot *j* of the bracket *f*, as does also the bent end *d* of the lever 36'. The strips are provided each with a contact *k* for engagement with the corresponding upper and lower contact-points *l* and *m* of the bracket *f*. These contact-points *e* and *l* and *m* are of the binding-post variety, so that wires *n* may be connected thereto, so that 15 separate circuits may be opened and closed at distant points upon operation of the contact-lever 36'. This contact-lever is provided with a central perforation *o* for engagement upon a piston in the same manner as is 20 disposed the aforesaid contact-lever 36. It will therefore be understood that the only difference in this form of the invention over the first form described is that provision is made for making and breaking a series of 25 circuits.

What is claimed is—

1. In an electropneumatic railroad signaling apparatus, a track-valve, an air-cylinder, a communicating passage between the track-valve and the air-cylinder, the latter having

an air-inlet, and a contact-lever pivotally associated with the air-cylinder.

2. In an electropneumatic railroad signaling apparatus, a spring-actuated track-valve, an air-cylinder in communication with the track-valve, a piston arranged for reciprocation in the air-cylinder and having a spring associated with the air-cylinder, the air-cylinder being provided with an air-inlet. 35

3. In an electropneumatic signaling apparatus, the combination with a railroad tie and rail, of a track-valve associated with the rail, an air-cylinder in communication with the track-valve, said air-cylinder having an inlet-port, a piston arranged within the cylinder above the air-inlet port, a spring associated with the piston, an arm associated with the top of the air-cylinder, an upright associated with the air-cylinder, and a contact-lever pivotally mounted in said arm 40 and associated with the piston and the said upright whereby electrical communication may be made and broken upon contact with the track-valve. 50

In testimony whereof I affix my signature 55 in presence of two witnesses.
